ELECTRONIC MICROANALYZER
MONITORINGJames Hillier, Cranbury, and Richard F. Baker,
Princeton, N. J., assignors to Radio Corpora-
tion of America, a corporation of Delaware

Application January 31, 1944, Serial No. 520,410

17 Claims. (Cl. 250—49.5)

1
This invention relates generally to electron optics and more particularly to an improved method of and means for monitoring the microanalyzing of materials by electron irradiation.

The invention is an improvement over the systems described in a copending U. S. application of James Hillier, Serial No. 505,572, filed October 3, 1942, entitled "Electronic microanalyzer," which describes the generation of an electron probe, having extremely minute cross-sectional area, which is focused upon a minute area of the electron permeable material to be analyzed. Electrons which are transmitted, or modified, or reflected from the material by the impinging electrons, are subjected to an electrical or magnetic deflecting field which deflects the electrons as a function of their velocities. The deflected electrons impinge upon a fluorescent screen for visual observation of the electron velocity distribution pattern, or the electrons impinge upon a photographic plate for providing a permanent record of the pattern. Means are included for observing upon an auxiliary fluorescent screen the portion of the specimen upon which the electron probe impinges only during intervals when the deflecting field is not present. Means also are provided for adjusting the position of the material under observation with respect to the axis of the electron probe.

The operation of the electronic microanalyzer is based on the fact that when electrons pass through matter some of the energy of the electrons is transformed into X-ray radiation energy. Since this transformation of energy takes place according to the accepted quantum theory, it follows that for an electron to excite a photon of the characteristic X-ray radiation of an element the electron must lose energy in an amount equal to or greater than that contained in the X-ray photon. Thus among the electrons leaving a specimen containing a certain element there will be a predominance of those electrons which have lost an amount of energy equal to or slightly greater than the energy contained in a single photon of the characteristic X-ray radiation of that element. The velocity spectrum of the electrons leaving a point of the specimen will have "lines" corresponding to the important X-ray lines of all the elements contained in the area of the specimen being examined. Electron microanalysis offers several advantages over ordinary methods of microanalysis. Sub-microscopic regions of a specimen can be analyzed without removing the region from the specimen or without changing it in any way.

2
By means of the improved electron microscope associated with the analyzer, as described in detail hereinafter, the area of the specimen analyzed can be observed and monitored at all times, so that the relationship of the region examined to the remainder of the specimen can be determined continuously, independently of and simultaneously with the electron velocity analysis.

10 The apparatus required for electronically analyzing materials is similar in many respects to the conventional electron microscope. The principal difference resides in the fact that electrons which impinge upon or penetrate the substance under observation are subjected to deflecting electric or magnetic fields whereby they are deflected amounts proportional to their velocities before impingement upon the observation screen. Accordingly, if desired, the invention 15 may take the form of a relatively simple attachment for conventional electron microscopes to permit microanalysis by electronic methods. Furthermore, the electrons which are velocity analyzed are those which are scattered in passing through the specimen to some predetermined angle from the irradiating electron beam axis. The thus scattered electrons have lost energy due to inelastic collisions with the specimen, hence 20 they are especially suitable for the desired microanalysis, thereby providing improved velocity indications over the analysis of directly transmitted electrons as described in said copending application.

Among the objects of the invention are to provide an improved method of and means for microanalyzing materials permeable to electron irradiation. Another object of the invention is to provide an improved method of and means for electronically analyzing minute specimens of 35 materials. A further object of the invention is to provide an improved method of and means for electronically analyzing materials by subjecting a minute area of the material to electron irradiation, subjecting electrons derived from said 40 irradiated area to the effects of a deflecting field, and indicating the relative velocities of the electrons subjected to said field. Another object is to provide improved means for securing a permanent record of the relative velocities of said 45 electrons subjected to said deflecting field. A still further object includes an improved method of and means for subjecting a minute area of a substance to electron irradiation, subjecting electrons transmitted by said substance to a uniform 50 magnetic field, and indicating the relative 55

velocities of electrons subjected to said magnetic field.

Further objects of the invention include an improved method of and means for electronically microanalyzing materials permeable to electron irradiation by irradiating a minute area of said material, selecting at least a portion of the electrons derived from said material, subjecting said selected electrons to a deflecting field, indicating the relative velocities of said electrons subjected to said field and forming an enlarged optical image of the specimen continuously, independently of and simultaneously with said electron velocity indications. Another object is to provide an improved method of and means for electronically microanalyzing materials wherein electrons derived from a minute portion of said materials are velocity analyzed, and other electrons derived from said material form continuously and independently of said velocity analysis an enlarged visual image of said material, and controlling said visual image by external adjustment of a light optical lens system.

The invention will be further described by reference to the accompanying drawings of which Figure 1 is a schematic diagram of one embodiment thereof, Figure 2 is a schematic diagram of a second embodiment thereof, Figure 3 is a cross-sectional elevational view of a preferred embodiment of the invention according to the schematic diagram of Figure 1, Figure 4 is an enlarged fragmentary elevational view of a portion of Figure 3, and Figure 5 is a plan view of the devices of Figure 4. Similar reference characters are applied to similar elements throughout the drawings.

Referring to Figure 1, an electron source 1, which may be provided by a conventional thermionic cathode which is maintained at a relatively high negative potential with respect to an apertured anode electrode, neither of which are shown herein, is imaged by a pair of electron lenses 2, 3 respectively, to irradiate an extremely minute area of an electron permeable object 4. The electron lenses 2, 3, respectively, may be of either the electromagnetic or electrostatic types customarily employed in electron optical apparatus such as, for example, electron microscopes. If electromagnetic lenses are employed, as shown in the drawings, the focus of said lenses may be adjusted by means of series resistors 5, 5' connected between one terminal of each of the magnetic lenses and an energizing current source such as, for example, a battery 6.

A third electron lens 8, which may be energized through a third variable resistor 9 by current from the battery 6, is disposed coaxially with the first and second electron lenses 2, 3.

The electrons transmitted by the specimen 4 may be selectively subjected to a magnetic field within a deflection chamber 13. The magnetic field will cause the transmitted electrons to follow substantially semi-circular paths and impinge upon an image screen or photographic plate 14. The magnetic field within the deflection chamber 13 will deflect the electrons different amounts determined by their respective velocities whereby a velocity distribution pattern will be provided upon the image screen 14. The focus of the pattern is controlled by varying the current through the third lens 8 by adjusting the resistor 9.

A pair of deflecting coils 21, 21' energized by the battery 6 through an adjustable fourth resistor 22 are symmetrically disposed adjacent the specimen 4 and between the specimen and the deflection chamber 13. The deflecting coils 21, 21'

provide deflection of the principal electron beam transmitted by the specimen to an auxiliary fluorescent screen 10, adjustably positioned within the specimen chamber but displaced from the main beam axis. A prism or mirror 12, cooperating with a conventional light microscope 11 permits an enlarged image of the electron irradiated portion of the specimen 4 to be observed continuously, also independently of and simultaneously with the velocity analysis of the electrons introduced into the deflection chamber 13. Some of the electrons transmitted by the specimen are scattered or reflected thereby at angles other than the electron beam axis. These scattered electrons are deflected by the deflecting coils 21, 21', and are passed into the deflection chamber to be velocity analyzed. It therefore will be seen that an axial portion of the specimen transmitted electrons may be employed for continuously observing an enlarged image of the specimen, while other transmitted electrons from the specimen are velocity analyzed during desired intervals.

It should be understood that the magnetic field within the deflection chamber 13 may be established in any desired manner. It also should be understood that the electron lens system described may be modified in any known manner to provide a suitable electron probe of convenient cross-sectional area for irradiation of the specimen 4, and that the third electron lens 8 may be omitted entirely if the deflection chamber 13 and image screen 14 are disposed in close relation with the specimen 4.

Figure 2 is similar to Figure 1, differing in that an electric field is substituted for the magnetic field within the deflection chamber 13 of the device of Figure 1 for deflecting the electrons derived from the specimen 4 in accordance with their relative electron velocities. In order to provide relatively long electron paths through an electrostatic field, two arcuate concave electrodes 18, 19, separated by an air gap 20, are disposed in cooperative relation to provide an arcuate tubular electrostatic deflecting element which will cause the deflected electrons to impinge upon the screen 14 to provide a velocity distribution pattern thereon. A pair of deflecting coils 21, 21', symmetrically disposed adjacent the specimen 4 between the specimen and the deflection chamber 13, provide deflection of the principal electron beam transmitted by the specimen to an auxiliary fluorescent screen 10, which, cooperating with a prism or mirror 12 and a light microscope 11, provides an enlarged image of the electron irradiated portion of the specimen continuously in the same manner as described in Figure 1. Similarly, some of the electrons transmitted by the specimen but refracted or scattered from the beam axis, due to inelastic collisions within the specimen, are deflected by the deflecting coils 21, 21' to enter the gap 20 between the electrostatic deflecting elements 18, 19 for the electron velocity analysis described heretofore.

Figure 3 is a preferred embodiment of the device described in Figure 1 constructed according to conventional electron microscope practice. The electron source includes a thermionic cathode 25 which is supported by a high potential insulator 26 and connected to a terminal 27 which is maintained at high negative potential. An apertured anode electrode 28, which is maintained at a high positive potential with respect to the thermionic cathode 25, provides an electron beam having relatively high electron velocity. The first electron lens 2 is illustrated as a conventional elec-

tromagnetic electron microscope lens including a winding 29 having a pole piece aperture 30. The second electron lens 3 forms a unitary structure with the first electron lens 2 and includes a second winding 31 and a second pole piece aperture 32.

The specimen 4 is supported by a conventional specimen supporting element 33 which may be adjusted with respect to the electron beam axis by an external adjusting knob 34 operating through a conventional bellows joint 35 disposed adjacent an aperture 36 in the outer wall 37 of the supporting structure. The third electron lens 8 may be similar to the first and second electron lenses 2, 3, respectively, and includes a third winding 38 and a relatively large pole piece aperture 39. A shutter 40, operated by an externally controlled knob 41, is interposed between the third electron lens 8 and an aperture 42 in the wall of a deflection chamber 43 which is secured to the supporting structure of the third electron lens.

A magnetic winding 44, disposed external to the deflection chamber 43, provides a magnetic field therein for deflecting electrons entering the aperture 42 and for causing them to impinge upon a photographic plate 45 for providing a permanent record of the deflected electron pattern. The photographic plate 45 may be removed from the deflection chamber 43 by means of an air lock or any other structure customarily employed in conventional electron microscopes. A hinged fluorescent screen 46, pivoted adjacent one edge of the photographic plate 45, may be rotated to cover the plate 45 for providing a visual image of the electron velocity distribution pattern. The visual image on the fluorescent screen, when in position 47, shown in dash lines, may be observed through a window 48 adjacent to and normal therewith.

The auxiliary beam deflecting coils 21, 21', disposed within the specimen chamber, may be supported by the adjustable specimen supporting element 33 symmetrically with respect to the specimen 4. The auxiliary fluorescent screen 10, prism or mirror 12 and the objective lens 23 of the light microscope may be supported within the specimen chamber on a movable support 24, the position of which may be adjusted by an external adjusting knob 50. The remainder of the light microscope assembly 51 may be supported on the exterior wall 37 of the specimen chamber, by means of a bracket 52, to cooperate with the microscope objective lens 23 through a window 53 sealed in the specimen chamber wall. It should be understood that the adjustment of the position of the movable support 24 by the knob 50 may be accomplished by any conventional Sylphon or packing gasket in the specimen chamber wall 37. The details of the preferred embodiment of these features of the invention will be described in Figures 4 and 5 hereinafter. When the magnetic field is established within the deflection chamber 43 by energization of the magnetic winding 44, the velocity distribution pattern may be observed through the window 48 upon the hinged fluorescent screen 46 when it is in the position indicated by the dash lines 47. The shutter 40 may then be closed to prevent electrons entering through the aperture 42 and the fluorescent screen 46 rotated to its vertical position, as indicated in the drawings. The shutter 40 may then be opened for a desired interval to expose the photographic plate 45.

Referring to Figures 4 and 5, a transverse sup-

port 55 extending between the walls 37 of the object chamber, supports two parallel disposed guide rods 57, 59 which are journaled in apertures in the transverse support 55, and disposed

5 symmetrically with respect to the central axis of the specimen 4. The remaining end of the first guide rod 57 is supported in aperture 61 in the specimen chamber wall 37, and the remaining end of the second guide rod 59 extends through 10 a bushing 63 in the specimen chamber wall 37 and is terminated in a control knob 50. The bushing 63 includes a packing gasket 65 which effectively seals the vacuum within the specimen chamber. A portion 67 of the second guide rod 15 59 is threaded to receive a complementarily threaded bushing on the movable support 24 which carries the light microscope objective lens assembly 23, the mirror 12 and the auxiliary fluorescent screen 10. Adjustment of the adjusting knob 50 thereby provides transverse adjustment of the light microscope objective 23, the mirror 12 and the auxiliary fluorescent screen 10 with respect to the central axis of the specimen chamber.

20 The eye piece portion 51 of the light microscope is supported on the exterior of the specimen chamber wall 37 by means of a bracket 52 whereby the objective and eye piece portions of the light microscope cooperate through the window 53 which is sealed in the specimen chamber wall 37.

25 The movable specimen support 33 which is adjustable by means of the specimen adjusting knob 34 coupled to the specimen support 33 through the Sylphon 35, supports the magnetic deflecting coil assemblies 21, 21' which are symmetrically arranged with respect to the specimen 4 and the auxiliary fluorescent screen 10, but which are offset slightly from the electron beam axis 68.

30 The deflecting coil assemblies 21, 21' include 35 parallel-disposed magnetic pole pieces 69, 69', which support windings 71, 71' respectively. Adjustment of the specimen support 33 thereby adjusts the position of the deflecting coil assemblies 21, 21', and the specimen simultaneously with respect to the electron beam axis 68.

35 As explained heretofore, the normal electron beam 73 penetrating the specimen 4 is deflected by the deflecting coils 21, 21' to impinge upon the auxiliary fluorescent screen 10 for continuous 40 observation of the electron-irradiated portion of the specimen 4. Some of the electrons refracted or scattered from the normal electron beam axis 68 are deflected by the deflecting coil assemblies 21, 21' to provide a second electron beam 75 which passes through the pole piece aperture 39 of the third electromagnetic lens 8, and enters the deflection chamber 43 for the velocity analysis function of the specimen described heretofore.

45 It should be understood that the angle of incidence of the irradiating electron beam may be varied by rotating the specimen 4 with respect to the electron beam axis. It also should be understood that the low and high velocity electrons derived from the electron irradiated specimen may be separated by any other means known in the art. Similarly, the modification of the invention disclosed in Figures 3, 4 and 5 may be adapted readily to the device described in Figure 2 by substituting the electrostatic deflecting field for the electromagnetic deflecting field of the device of Figure 1.

50 Thus the invention described comprises several modifications of an improved method of and means for microanalyzing materials by electron irradiation wherein continuous observation of

the minute electron irradiated portion of the specimen is provided independently of and, if desired, simultaneously with the velocity analysis of electrons derived from said irradiated specimen. Improved electron velocity analysis is provided by utilizing electrons scattered within predetermined angular limits in passing through the specimen due to inelastic collisions within said specimen.

We claim as our invention:

1. In an electron microanalyzer including means for providing an electron probe having extremely minute cross-sectional area, means for supporting an object, means for irradiating said object by said electron probe, an electron sensitive screen responsive to electrons from said object, and means interposed between said screen and said object means providing a field for deflecting said electrons derived from said object as a function of their velocity to provide an electron velocity distribution image on said screen, the improvement comprising electronic means for continuously providing a visible image of said electron probe irradiated portion of said object means independently of and simultaneously with said deflection of said electrons.

2. An electron microanalyzer including electron beam generating means and electron beam focusing means for providing an electron probe having extremely minute cross-sectional area, means for supporting an object, means for irradiating said object by said electron probe, an electron sensitive screen responsive to electrons from said object, means interposed between said screen and said object means providing a field for deflecting said electrons derived from said object as a function of their velocity to provide an electron velocity distribution image on said screen, and electronic means for continuously providing a visible image of said electron probe irradiated portion of said object means independently of and simultaneously with said deflection of said electrons as a function of their velocity.

3. In an electron microanalyzer including electron beam generating means and electron beam focusing means for providing an electron probe having extremely minute cross-sectional area, means for supporting an object substantially permeable to electron irradiation, means for irradiating said object by said electron probe, an electron sensitive photographic screen responsive to electrons from said object, and means interposed between said screen and said object means providing a field for deflecting said electrons derived from said object as a function of their velocity to provide an electron velocity distribution image on said screen, the improvement comprising electronic means for continuously providing a visible image of said electron probe irradiated portion of said object means independently of and simultaneously with said deflection of said electrons as a function of their velocity.

4. Apparatus of the type described in claim 1 including means disposed within said deflecting means selectively providing a visual image of said screen.

5. Apparatus of the type described in claim 3 characterized in that said image means includes a fluorescent screen for continuously observing said electron probe irradiation of said object, and means for optically magnifying said image on said fluorescent screen.

6. Apparatus of the type described in claim 3 characterized in that said image means includes

7. In an electron microanalyzer including a fluorescent screen for continuously observing said electron probe irradiation of said object, means for optically magnifying said image on said fluorescent screen and externally adjustable means for orienting said optical magnifying means and said fluorescent screen with respect to said electron irradiated portion of said object.

8. In an electron microanalyzer including means for providing an electron probe having extremely minute cross-sectional area, an object substantially permeable to electron irradiation, means for irradiating said object by said electron probe, an electron sensitive screen responsive to electrons from said object, and means interposed between said screen and said object means providing a field for deflecting said electrons derived from said object as a function of their velocity to provide an electron velocity distribution image on said screen, the improvement comprising electronic means for continuously providing a visible image of said electron probe irradiated portion of said object independently of and simultaneously with said deflection of said electrons.

9. In an electron microanalyzer including means for providing an electron probe having extremely minute cross-sectional area, means for supporting an object substantially permeable to electron irradiation, means for irradiating said object by said electron probe, an electron sensitive screen responsive to electrons from said object, and means interposed between said screen and said object means providing a magnetic field for deflecting said electrons derived from said object as a function of their velocity to provide an electron velocity distribution image on said screen, the improvement comprising means for continuously providing a second electron image of said electron probe irradiated portion of said object means independently of and simultaneously with said deflection of said electrons.

10. Apparatus of the type described in claim 2 including an externally operable shutter interposed between said object supporting means and said screen for controlling the electron exposure time for said screen, said object second image means being independent of said shutter.

11. The method of electron microanalyzing a material comprising generating an electron probe of minute cross-sectional area, electron irradiating said material by said electron probe, subjecting electrons derived from said object to a field to deflect said electrons as a function of electron velocity, indicating the relative velocities of said derived electrons, and forming continuously and electron optically a visual image of said electron irradiated portion of said material, said image formation being independent of said

electron deflection as a function of electron velocity.

12. The method of electron microanalyzing a material comprising electron irradiating a minute cross-sectional area of said material, indicating the relative velocities of the electrons derived from said area of said material in response to said irradiation and continuously forming electron optically and simultaneously with said velocity indications an enlarged visual image of said irradiated area.

13. An electron microanalyzer including electron beam generating means and electron beam focusing means for providing an electron probe having extremely minute cross-sectional area, means for supporting an object, means for irradiating said object by said electron probe, an electron sensitive screen responsive to electrons from said object, means interposed between said screen and said object means providing a field for deflecting said electrons derived from said object as a function of their velocity to provide an electron velocity distribution image in said screen, and magnetic beam deflecting means interposed between said object supporting means and said deflecting field means for continuously providing a visible image of said electron probe irradiated portion of said object means independently of and simultaneously with said deflection of said electrons as a function of their velocity.

14. An electron microanalyzer including electron beam generating means and electron beam focusing means for providing an electron probe having extremely minute cross-sectional area, means for supporting an object substantially permeable to electron irradiation, means for irradiating said object by said electron probe, an electron sensitive photographic screen responsive to electrons from said object, and means interposed between said screen and said object means providing a field for deflecting said electrons derived from said object as a function of their velocity to provide an electron velocity distribution image on said screen, the improvement comprising magnetic beam deflecting means interposed between said object supporting means and said deflecting field means and a fluorescent

screen responsive to electrons deflected from said object for continuously providing a visible image of said electron probe irradiated portion of said object means independently of and simultaneously with said deflection of said electrons as a function of their velocity.

15. Apparatus of the type described in claim 3 characterized in that said image means includes a fluorescent screen for continuously observing said electron probe irradiation of said object, means including a light microscope having its objective focused upon and movable with said fluorescent screen for optically magnifying said image on said fluorescent screen and externally adjustable means for orienting said optical magnifying means and said fluorescent screen with respect to said electron irradiated portion of said object.

16. The method of electron microanalyzing a material comprising electron irradiating a minute cross-sectional area of said material and indicating the relative velocities of the electrons derived from said area of said material which electrons have lost energy in passing through said material and which have been scattered between predetermined angular limits from the axis of said irradiating electrons.

17. In an electron microanalyzer including means for providing an electron probe having extremely minute cross-sectional area, means for supporting an object, means for irradiating said object by said electron probe, an electron sensitive screen responsive to electrons from said object, and means interposed between said screen and said object means providing a field for deflecting said electrons derived from said object as a function of their velocity to provide an electron velocity distribution image on said screen, the improvement comprising second beam deflecting means interposed between said object means and said first deflection means for deflecting into said field electrons which have been scattered within predetermined angular limits due to inelastic collisions within said object.

JAMES HILLIER.
RICHARD F. BAKER.
